GRINDING WHEEL DRESSING DEVICE

Gustave Helding, Chicago, Ill.

Application October 2, 1943, Serial No. 504,657

7 Claims. (Cl. 125—11)

This invention relates to improvements in grinding wheel dressing devices and it consists of the matters hereinafter described and more particularly pointed out in the appended claims.

One of the objects of the present invention is to provide a device whereby the peripheral face of the grinding wheel may be quickly and accurately dressed, with precision, to provide the desired cross sectional arc or curvature therefor.

Another object of the invention is to provide a device of this kind which may be quickly adjusted to provide either a relatively small arc, as for the corners of the peripheral face of the wheel, or any one of a number of larger arcs for the cross sectional shape of said face.

Furthermore it is an object of the invention to provide a device of this kind which is of simple construction and is easily manipulated in adjusting the same and which positively holds the position into which it is adjusted so that the desired dressed face of the wheel is true and accurate about its entire periphery.

The above mentioned objects of the invention, as well as others, together with the many advantages thereof will more fully appear as the specification proceeds.

In the drawings:

Fig. 1 is a top plan view of a grinding wheel dressing device, on a full size scale, embodying the preferred form of the invention.

Fig. 2 is a longitudinal vertical view through the device as taken substantially on the line 2—2 of Fig. 1, parts being in section and parts in elevation, illustrating the manner of setting the device for a dressing operation.

Fig. 3 is a detail longitudinal vertical sectional view through parts of the device shown in Figs. 1 and 2 and as taken on the line 3—3 of Fig. 1 when the parts are in a position changed from that shown in said Fig. 1.

Fig. 4 is a perspective view of a certain gauge stem forming a part of the device and which will be more fully mentioned later.

Fig. 5 is a detail transverse vertical sectional view through a part of the device as taken on the line 5—5 of Fig. 1.

In general the improved device is one for dressing grinding wheels as embodied in certain machines capable of accurate grinding of machined parts. It includes a base adapted to be secured in a fixed position with respect to the wheel to be dressed and a swing plate having a pivotal connection therewith so as to swing in an arc relatively to the base, to either side of a predetermined position thereon.

The swing plate has a perpendicular post thereon in which a tool, with an abrasive point such as a diamond, is mounted for adjustment toward and away from a gauge stem and by which the radius of the curve or arc to be made by the point may be accurately determined.

Referring now in detail to that embodiment of the invention illustrated in the drawings, the improved device includes an elongated rectangular base 10 and a swing plate 11 spaced above the same. The swing plate is somewhat longer than the base plate so as to overhang the same at one end where it is provided with a handle 12.

The swing plate has a pivotal connection at its 15 other end upon the base so as to be capable of a lateral swinging movement, to one side and the other of a predetermined position wherein the longitudinal edges of the base and swing plate coincide. This connection includes a bushing or 20 stud 13 having an axial bore 14 and the lower end 15 of said stud is threaded into an opening 16 in the base. About the upper end of the opening 16 is a shallow recess 17 and in which engages a boss 18 on the bottom end of one of a pair of 25 lower and upper spacers 19 and 20 respectively. The spacer 19 is attached to the base 10 by means of screws 21 that pass up through the base from below. The spacer 20 includes an extension 20a that passes up through that end of the swing 30 plate 11, opposite the handle 12 to provide a bearing for a swinging movement thereof.

The top end of the stud 13 carries a radial flange 22 and disposed between said flange and the top surface of the swing plate is a washer-like 35 disc 23.

When the bottom end 15 of the stud is threaded into the opening 16 in the base plate, said studs hold the part together in assembled relation so that the swing plate may be swung laterally in 40 either direction from the predetermined position before mentioned and as appears in Fig. 1.

To hold said base and plate in this predetermined position I provide in one margin of each thereof, aligned openings 24 and 25 respectively, 45 as shown in Fig. 5. A pin 26, having a head 27, is inserted through the opening 25 so that its bottom end enters the opening 24. This assures the alignment of said plates. A finger actuatable set screw 28 has threaded engagement through one side edge of the plate 11 so as to engage the pin 26 and hold the same in place. When it is desired to swing the plate 11 laterally, in either direction 50 from the position shown in Fig. 1, the screw 28 is loosened and the pin 26 is pulled upwardly and 55 freed from the hole 24 where it may be locked in

the freed position by again tightening the screw 28.

Rising from the top side of the swing plate, on the median line thereof, is a tool or supporting post 30. The bottom end of this post has a threaded boss 31 which is engaged in a threaded opening 32 in said plate 11. A similar opening 33 is provided in the plate 11 a greater distance away from the axis of the pivotal connection before mentioned than is the opening 32. The boss 31 is locked in the opening 32 or 33, as the case may be, by means of a set screw 34 as in Fig. 1.

In the top end of the post 30 is a transverse hole 35 which snugly receives a stem-like tool 36 which may be moved back or forth through said hole for adjustment and then locked in the adjusted position by a finger actuatable screw 37. One end of this tool is pointed as at 38 and this end of said tool is directed toward the axis of the pivotal connection between the base 10 and plate 11. The tip of said tool end is provided with an abrasive element 39 that is hard enough to cut a grinding wheel. A commercial diamond well serves as the element 39.

In Fig. 4 is illustrated in perspective a gauge stem 40 of substantial length and of a diameter to have a snug fit in the bore 14 of the bushing or stud 13. One side of the upper end of this stem is cut away to form a flat face 41, the plane of which includes the axis of the stem. In the same side of the stem toward its lower end is located a recess 42 presenting a flat surface as shown in Figs. 2 and 4.

When the stem 40 is in place with its bottom end disposed in the bore 14 of the bushing or stud 13, its top end flat face 41 should stand in a plane perpendicular to the axis of the tool 36 when the base 10 and plate 11 are in the predetermined position before mentioned. To assure that the face 41 is so positioned, I provide means on the swing plate that coat with the recess 42 and such means is as follows:

Rising from that side of the swing plate opposite the set screw 34 is a boss 43 having a longitudinally extending opening 44 therein. This boss carries a bottom end stud 45 that fits in an opening 46 in the swing plate 11 and is secured therein by a set screw 47 as indicated in dotted lines in Fig. 3. Below and parallel with the opening 44 is another and smaller opening 48 in which one end of a pin 49 has a drive fit; the other end extending toward the handle end of the swing plate 11.

A stem 50 has a sliding rotative bearing in the bore 44 and one end carries a right angled stop arm 51. An expansion spring 52 surrounds the stem between the boss 43 and arm 51 and normally urges the stem 50 and arm 51 toward the left as viewed in Figs. 2 and 3. The stop arm is so formed that when its free end traverses the median line of the plate 11, as shown in Fig. 1, one side of the arm will engage in the recess 42 of the stem 40 as shown in Fig. 2. When so engaged, this assures that the face 41 at the top end of said stem, stands perpendicularly to the axis of the tool 36 when the two plates 10 and 11 coincide at the edges.

The other end of the stem 50 has one end 53 of a tubular body 54 secured thereto and this end is formed as a radial flange in which is a longitudinal opening 55. The other end of said body is formed as a knurled finger grip 56. The opening 55 is so formed as to permit the pin 49 to pass therethrough when the body 54 is turned so that the opening 55 registers with the pin. When the

body is pulled or drawn to the right, as shown in Fig. 3 and then turned about the axis of the stem 50, the stop arm is withdrawn from the recess 42 and the opening 55 is moved out of register with the pin 49. The parts are thus held in the retracted position shown in Fig. 3 wherein the spring 52 is in compression.

Assume that it is desired to dress the peripheral corners of a grinding wheel so that said corners will have a curvature of say $3\frac{1}{2}$ " in diameter. The base 10 and plate 11 are secured in the predetermined position before mentioned, by use of the pin 26 as before described. The stem 40 is then disposed in the bore 14 and is turned so that its face 41 is approximately perpendicular to the axis of the tool stem 36. The body 54 is then manipulated to dispose the stop arm 51 in the recess 42 of the stem 40 and this not only assures the perpendicularity of the face 41 relative to the tool 36 but detachably locks the gauge stem 40 in place. The stem is further locked against turning by reason of the engagement of the pin 49 in the opening 55 of the flange 53. One or more thickness gauge blocks 57 (see Fig. 2), usually found in every machine shop, providing a thickness of $3\frac{1}{2}$ " is then held flatwise against the face 41 of the stem 40, after which the tool 36 is moved toward said block until the abrasive element 39 engages therewith and the tool is then locked in place by tightening the screw 37. The thickness block 57 is then removed and this leaves the element 39 spaced $3\frac{1}{2}$ " from the axis of the bore 14 in the stud 13 and which is also the axis of the pivotal connection between the base and wing plate. The body 54 is then pulled to the right far enough so that the flange 53 clears the pin 49, after which said body is turned clockwise so that the opening 55 in the flange 53 moves out of register with the pin as shown in Fig. 3. This releases the stem 40 which is then removed from the bore 14 in the stud 13.

The device as a whole is now moved into a position adjacent one corner of the periphery of the wheel to be dressed so that the element 39 is properly positioned with respect thereto. The set screw 28 is then loosened and the pin 26 withdrawn from its engagement in the hole 24 in the base 10 and then locked in the withdrawn position by again tightening the screw 28. The swing plate 11 is now free to swing about the pivotal connection with the base and as the element 39 has been positioned $3\frac{1}{2}$ " of an inch from the axis of said connection, it will, when the plate 11 is swung laterally, round off the corner of the grinding wheel so as to have a radius of $3\frac{1}{2}$ ".

It is apparent that by adjusting the tool 36 in the post 30 outwardly or to the right, as shown in Fig. 2, the cutting diameter afforded by the element 39 is increased. However, each time an adjustment is to be made, the stem 40 is replaced as before mentioned and the gauge block is used to make the adjustment.

With the post 30 disposed in the opening 32, adjustments forming minute radii, say substantially zero to one over an inch may be afforded. If a larger radius is desired for the element 39, the post 30 is removed from the opening 32 and disposed in the opening 33.

The device is accurate and assures precision setting of the element 39 from substantially zero to indeed relatively large diameters whereby a multitude of dressed faces may be provided on grinding wheels.

While in describing the invention I have referred in detail to the form arrangement and

construction of the parts involved, the same is to be considered only in the illustrative sense so that I do not wish to be limited thereto except as may be specifically set forth in the appended claims.

I claim as my invention:

1. A device of the kind described embodying therein a base, a plate disposed above the base and having a pivotal connection therewith for a lateral swinging movement out of and into a predetermined position relative to the base, a stem removably mounted on the base coaxially with said pivotal connection and extending above said plate and having a surface portion coincident with the axis of said pivotal connection, and a transverse recess below said surface portion, a tool having a wheel cutting element at one end thereof mounted on said plate for adjustment toward and away from said surface portion, and manually operable means engageable in and disengageable from said recess in said stem for detachably securing said stem against axial withdrawal from and against turning relative to said base.

2. A device of the kind described embodying therein a base, a plate having a plurality of spaced tool-post receiving apertures disposed above the base and having a pivotal connection therewith for a lateral swinging movement out of and into a predetermined position relative to the base, a stem removably mounted on the base coaxially with said pivotal connection and extending above said plate and having one side of its free end cut away to form a flat surface portion coincident with the axis of said pivotal connection and having a bottom shoulder, said stem having a transverse recess below said surface portion, a tool post mounted on said plate, a tool having a wheel cutting element at one end thereof slidably mounted in the free end of said tool post, for adjustment toward and away from said surface portion, means engageable and disengageable in said recess in said stem for detachably securing the stem to the base with said flat surface portion in a definite position relative to said tool when said plate is in a predetermined position on the base and prevent axial withdrawal therefrom, and means for releasably locking said plate in a predetermined position on said base.

3. A device of the kind described embodying therein a base, a plate disposed above the base and having a pivotal connection therewith for a lateral swinging movement into and out of a predetermined position on the base, a stem removably mounted on the base coaxially with said pivotal connection and extending above the plate and having a flat surface portion coincident with the axis of said pivotal connection, and a transverse recess below said surface portion, a tool having a wheel cutting element at one end there-

of mounted on said plate for adjustment toward and away from said surface portion, and manually operable means engageable in and disengageable from said recess in said stem for detachably securing the stem to and against turning relative to said base with said flat surface portion in a definite position relative to said tool.

4. A device of the kind described embodying therein a base, a plate provided with a plurality of spaced post-receiving apertures disposed above the base and having a pivotal connection therewith for a lateral swinging movement into and out of a predetermined position on the base, said pivotal connection including a bushing fixed to the base and having a bore therein, a stem removably disposed at one end in said bore and having its other end extending above said plate, the upper end portion of said stem having a flat surface portion coincident with the axis of the pivotal connection, a tool having a wheel cutting element at one end thereof mounted on the plate for adjustment toward and away from said surface portion, said stem having a recess at one side thereof below said flat surface portion, means mounted on said plate and including a part engageable in the recess in the stem for holding the same in a definite position in said bore and prevent withdrawal therefrom, and means carried by said plate for locking said plate to said base when said tool is being adjusted relative to said surface portion.

5. A device of the kind described embodying therein a base, a plate disposed above the base and having a pivotal connection therewith for a lateral swinging movement into and out of a predetermined position on the base, said pivotal connection including a bushing fixed to the base and having a bore therein, a stem removably disposed at one end in said bore and having its other end extending above said plate, the upper end portion of said stem having a flat surface portion disposed coincident with the axis of said pivotal connection, the stem having a recess in one side below said flat surface portion, a tool having a wheel cutting element at one end thereof mounted on the plate for adjustment toward and away from said flat surface portion, and means carried by said plate and adapted to be removably engaged in said recess for holding the stem in a position with said flat surface portion perpendicular to the tool.

6. The device according to claim 2, wherein means are provided to lock said tool in said tool post after adjustment.

7. The device according to claim 3, wherein said pivotal connection includes a bushing fixed to said base and having an axial bore therein in which one end of said stem seats.
